UNITED STATES PATENT OFFICE.

JOHN BLYTH, OF CHICAGO, ILLINOIS, ASSIGNOR TO TAPRELL, LOOMIS & COMPANY, OF CHICAGO, ILLINOIS, A CORPORATION OF ILLINOIS.

EASEL.

1,359,662.

Specification of Letters Patent. Patented Nov. 23, 1920.

Application filed October 17, 1919. Serial No. 331,365.

To all whom it may concern:

Be it known that I, JOHN BLYTH, of Chicago, in the county of Cook and State of Illinois, have invented certain new and useful Improvements in Easels; and I do hereby declare the following to be a full, clear, and exact description of the same, reference being had to the accompanying drawings, forming a part of this specification, and to 10 the reference numerals marked thereon.

My present invention relates to paper manufacturers and more particularly to picture and sign exhibiting and it has for its object to provide a simple, cheap and efficient easel the parts of which may be made from sheet material and which will embody a disappearing brace of a nature rendering it easy to assemble and to manipulate between its operative and inoperative positions. The invention is applicable to photographic mounts or folders and another object of the invention is to so apply the easel brace that it does not disfigure the mount in case the easel feature is not to be used. To these and other ends the invention resides in certain improvements and combinations of parts all as will be hereinafter more fully described, the novel features being pointed out in the claims at the end 30 of the specification.

In the drawings:

Figure 1 is a perspective view of a photographic mount and easel constructed in accordance with and illustrating one embodiment of my invention;

Fig. 2 is an enlarged rear view showing the brace in inoperative position;

Fig. 3 is a rear view of the brace alone on the scale of Fig. 2;

Fig. 4 is a section on the line 4—4 of Fig. 2, and

Fig. 5 is a similar section but showing the brace in operative position.

Similar reference numerals throughout 45 the several views indicate the same parts.

The photographic mount or folder that I have illustrated in the present instance comprises a double walled backing formed by securing a mounting board 1 against the body 2 of a folder having the usual side flaps 3 that are adapted to fold down and conceal the board 1 and its contents. The board has the usual corner retaining pockets 4 for engaging and holding the photograph 55 and these also operate to space the elements

1 and 2 of the complete backing. All of the parts of the device may be made of cardboard or stiff paper.

At about the center of the backing, I provide the rear wall 2 thereof with a horizontal slot 5. This slot may have no appreciable width so that it is more in the nature of a slit that is hardly noticeable and does not disfigure the folder in case the easel feature is not to be used. To provide 60 an easel, the brace shown in Fig. 3 is applied. This brace is also cut out of cardboard to embody an enlargement 6 at its lower end and an enlargement 7 at its upper end constituted by two rounded lateral ears 70 8. The brace is scored on the line 9 forming the junction between the enlargement 7 and the intermediate portion 10, which latter is tapered from this point downwardly toward the lower enlargement 6. 75

In assembling, the brace is inserted in the slot 5 of the backing by holding it in a canted position and inserting first one ear 8 and then the other in a manner familiar to those experienced with collapsible articles. When the mount is not in use, the brace may be shoved almost completely through the slot 5 so that the major portion thereof is accommodated between the walls 1 and 2 of the backing, as shown in Fig. 4, 80 and in dotted lines in Fig. 2, with only a portion of the enlargement 6 protruding. The enlargement 6 forms a finger-piece to grip the brace and when it is desired to move it to operative position, it is pulled 85 out as shown in Figs. 1 and 5 until stopped by the ears 8. This brings the scored line 9 into coincidence with the slot 5 and the brace is creased along this line so that the enlargement 7 is disposed at a slight angle. 90 The brace is now adapted to support the folder upright for the reason that its upper end edge frictionally engages the inner wall 1 of the backing and it is pinched between the walls of the slot along the scored and 100 creased line 9 at which point the slight angle formed abuts the upper wall of the slot.

The tapered intermediate portion of the brace permits it to slide freely in and out of the slot without danger of splitting and 105 enlarging the latter.

I claim as my invention:

1. In an easel, the combination with a backing having double walls, the rear wall being provided with a slot at an interme- 110

diate point, of a brace extending slidably through the slot and having a retracted position in which its major portion is accommodated between the said walls and an extended position in which it constitutes a leg adapted to rest upon the same surface as the lower portion of the backing.

5 2. In an easel, the combination with a backing having double walls, the rear wall being provided with a slot at an intermediate point, of a tapered brace of sheet material extending slidably through the slot with its narrower portion outermost, said brace having a retracted position in which 10 its major portion is accommodated between said walls and an extended position in which it constitutes a leg adapted to rest upon the same surface as the lower portion of the backing.

15 3. In an easel, the combination with a backing having double walls, the rear wall

being provided with a slot, of a brace extending slidably through the slot and having a retracted position in which its major portion is accommodated between the said walls, both the inner and outer ends of the brace being provided with enlargements wider than the slot to prevent the brace from passing entirely therethrough in either direction.

20 4. In an easel, the combination with a backing having double walls, the rear wall being provided with a slot, of a brace extending slidably through the slot and having a retracted position in which its major portion is accommodated between the said walls, said brace being provided with an enlargement wider than the slot at its inner end and creased on the junction line of such enlargement to dispose the latter at an angle 25 to the body of the brace.

JOHN BLYTH.
